UNITED STATES PATENT OFFICE.

SAMUEL E. NUTTING, OF CHICAGO, ILLINOIS.

ELECTRIC HEATER.

SPECIFICATION forming part of Letters Patent No. 515,693, dated February 27, 1894.

Application filed April 27, 1893. Serial No. 472,064. (No model.)

To all whom it may concern:

Be it known that I, SAMUEL E. NUTTING, of Chicago, Illinois, have invented certain new and useful Improvements in Electric Heaters, 5 of which the following is a specification.

My invention relates to that class of electric heaters in which a resistance wire or series of wires is used, and heat generated therein from the resistance of the wire to the 10 electric current flowing through the same; and the invention consists in the features, details and combinations hereinafter described and claimed.

In the drawings, Figure 1 represents a plan 15 view of my improved heater; Fig. 2 a sectional view of the same taken on the line 2 of Fig. 1; and Fig. 3 a plan view of a portion of the heater, with the outer covering removed and showing the method I employ for embedding 20 the resistance wires.

The object of my invention is to provide an 25 electric heater, composed of the resistance wires embedded in a non-electric conducting substance and covered with a non-electric 30 conducting flexible covering, in such manner as to protect the wires from direct contact with the air, the whole being light and durable, so that it may be moved easily from place to place.

35 A further object of my invention is to provide the heater proper with a covering of mineral wool, or similar substance, and provide the same with an outer envelope of textile fabric, preferably wool, entirely inclosing the heater proper and covering of mineral wool connecting the terminals of the resistance wires with an insulated cable for furnishing the heater with a supply of electric current.

While I prefer to show in the drawings my 40 invention as applied to a portable electric heater that may be used as a foot warmer, or to supply warmth to any desired portion of the body, I do not desire to be limited to this particular use, as I contemplate using it in 45 connection with various other purposes.

In my preferred construction, as illustrated 50 in the drawings, I employ a base A, formed of a sheet of flexible asbestos material, and secure on either side of the base a series of resistance wires, preferably formed of German silver arranged in a zig zag manner, to compensate for expansion and contraction of the

wire during its heating or cooling. The wires are separated from each other, and prevented from coming into electric contact with each other by means of the asbestos cord b. I then fill the space occupied by these wires, preferably, with a solution of silicate of soda, C, and then cover and inclose the wires in the solution with an outer covering D, preferably composed of flexible sheets of asbestos material. The silicate of soda becomes hardened, and acts as a cement to unite the base and outer covering, and secure them together. I then surround the outer covering of asbestos 65 material with a packing, E, preferably of mineral wool, and inclose the heater proper with its packing of mineral wool in an envelope G, formed preferably of a woolen cloth, and secure the same together by quilting or sewing 70 in any usual manner. I then attach to the terminals H and H' of the resistance wires an insulated cable, I, which is connected at its other end with a terminal connector K, adapted to be inserted into an ordinary socket 75 L, provided with a usual switch button, l, by which the electric current may be turned on or shut off at pleasure.

From the foregoing description it will be seen that I have provided an electric heater that is 80 light and portable. The various parts constituting the same are formed of flexible non-electric conducting materials, so that the same may be conformed to any desired shape, without destroying any of the parts or rendering 85 the heater less efficient.

I claim—

1. An electric heater, composed of electric wires provided with terminals embedded in a non-conducting cement and between two layers of a flexible, non-conducting material, substantially as described.

2. An electric heater, composed of electric wires provided with terminals embedded in a non-conducting cement and between two layers of a flexible non-conducting material, in combination with an outer covering of textile fabric, substantially as described.

3. In electric heaters, the combination of a base formed of a sheet of asbestos material, electric resistance wires attached to this base, an outer covering of flexible asbestos material, silicate of soda filling the space occupied by the resistance wires between the base and

outer covering and forming a cement to unite the same and hold the wires in place, and an outer covering of textile fabric forming an envelope for the heater proper, substantially as described.

4. In electric heaters, the combination of electric resistance wires embedded in a non-conducting cement, two layers of flexible non-conducting material forming an outer covering for the same, an outer envelope of textile fabric, a packing of mineral wool interposed between the envelope and the heater proper, substantially as described.

5. In electric heaters, the combination of

electric resistance wires embedded in a non-conducting cement, two layers of flexible non-conducting material forming an outer covering for the same, an outer envelope of textile fabric, a packing of mineral wool interposed between the envelope and the heater proper, a set of electric wires for connecting the heater proper with a terminal connector, and a terminal connector, substantially as described.

SAMUEL E. NUTTING.
